UNITED STATES PATENT OFFICE.

FRANK S. ROYER, OF CHICAGO, ILLINOIS.

SPARK PLUG.

Application filed January 15, 1921. Serial No. 437,552.

To all whom it may concern:

Be it known that I, FRANK S. ROYER, a citizen of the United States, and a resident of Chicago, in the county of Cook and State of Illinois, have invented certain new and useful Improvements in Spark Plugs; and I do hereby declare that the following is a full, clear, and exact description thereof, reference being had to the accompanying drawings, and to the characters of reference marked thereon, which form a part of this specification.

This invention relates to improvements in spark or ignition plugs for the ignition systems of explosion engines, and has for its objects to provide an improved construction and arrangement to protect the terminals of the plug from short circuiting due to the contact of oil with the terminals at the spark gap; to novel means for insulating the live terminal from the grounded side of the plug; to means for producing a durable, practically non-breakable plug, and to means for otherwise improving spark plugs.

In accordance with my invention, the terminals at the spark gap are enclosed within a chamber in the shell of the plug, the walls of which chamber are constructed to permit free access to said chamber of the combustible gaseous mixture under pressure and free egress therefrom of the flame of combustion towards and into the cylinder, while at the same time protecting the terminals from contact with oil that may be pumped into the cylinder because of leaky piston rings and other conditions. The openings into the terminal chamber can be formed between suitable baffle elements, which can be made integral parts of the plug chamber walls, and so arranged as to afford indirect passages for the gases to and from the chamber, and at the same time arranged to baffle oil thrown outwardly against the inner end of the plug so as to largely divert it away from said chamber and to divert any oil entering said chamber outwardly against the walls thereof and away from the sparking terminals and thereby prevent contact of the oil with the terminals at the spark gap.

The means for insulating the live terminal from the grounded part of the plug structure is constructed to avoid to a large

extent exposure of insulators, and especially porcelain, as heretofore employed, and to this end it is proposed to produce a substantially metal clad plug in that substantially all parts of the insulating elements of the plug are protected or supported, or both, by durable metal walls. The plug, therefore, becomes practically unbreakable, and is capable of rough usage without injury. This metal sheath or covering can also be formed in part to constitute radiating fins whereby the exposed portion of the plug may be maintained suitably cooled.

The construction of the plug body (shell and gland) is such that the spark gap between the terminals may be shortened by the simple expedient of removing parts of a laminated or shim washer that is located to form a gas tight joint between opposing joint forming shoulders of the body.

Other features of the construction which go to improve and simplify the spark plug will appear from the subjoined description.

As shown in the drawings;

Figure 1 is a side elevation, on an enlarged scale, of a spark plug embodying my invention.

Figure 2 is an axial section thereof.

Figure 3 is an end view of the plug.

Figure 4 is a cross section on the line 4—4 of Figure 2.

Figure 5 is a section on the line 5—5 of Figure 4.

Figure 6 is a perspective detail of the inner end of the plug shell.

In said drawings, 10 designates as a whole the metallic shell of the plug, which is formed with a reduced threaded portion 11 for engagement with the threaded opening in the cylinder wall or head, and with a larger polygonal portion 12. 13 designates a gland the threaded portion 14 of which engages interior screw threads in the shell and is formed with an annular, inwardly facing shoulder 15 that opposes a shoulder formed on the outer end of the shell.

Said gland 13 is formed with an outwardly extending neck 16 and said neck and gland are provided with a through axial opening to receive a rod 17 which extends at its outer end beyond the plug. The inner end of said rod constitutes the live ter-

5 minal of the plug and extends into and terminates within a chamber 30 formed in the inner reduced end of the shell. Said terminal is spaced from the grounded terminal 19 of the plug, also located within said 10 chamber 30 and grounded to the shell in a manner hereinafter to be described.

10 20 designates an insulating body usually made of porcelain. It is centered in any suitable way with respect to the gland 13, as by means of a reduced cylindric extension 21 which fits in an inwardly opening socket of the gland. The insulator 20 is sufficiently smaller than the shell as to be 15 out of contact with its metal wall and is rounded on its inner side within the enlarged portion of the shell chamber. The construction is such that the porcelain insulator can be made quite short. It has 20 an axial passage through which the terminal rod extends and closely fits, and said rod has fixed thereon a shoulder forming washer 29 that bears against the inner face of the insulator and is concaved to fit the inner convex end of said insulator.

25 The axial opening of the insulator is enlarged through the principal portion of its length and is coaxial with the axial opening of the gland and neck. The latter openings 30 are made considerably larger than the terminal rod 17, and said rod is insulated from the gland and neck by an insulating sleeve 23 that fits closely within said axial openings and itself closely surrounds said rod. 35 A suitable insulator for this purpose is a tube made of spirally wrapped sheet-mica, inasmuch as a tube or sleeve thus formed possesses considerable flexibility and does not easily break under differential temperatures in itself and in the contacting metal parts, and also because it is a material that readily adapts itself to the rather close dimensions indicated, and at the same time is durable and efficient, especially when 40 closed and metal supported in the manner shown.

45 The laminated insulator sleeve 23 extends inwardly beyond the gland 13 into the opening or socket 22 of the insulator 20 a distance to provide a long current leakage path between the said terminal rod and the gland. The said insulator sleeve 23 extends a substantial distance outwardly beyond the neck and the outer end of the terminal rod 17 is 50 insulated from said neck by a suitable insulating washer 24 having a central opening into which closely fits said insulator sleeve or tube 23. The said washer can, and preferably is made of sheet-mica, the laminæ of 55 which are pressed and held firmly between inner and outer washers 25, 26 by the clamping action of a nut 27 that cooperates against a shoulder formed by the outer end of the neck 16. Said terminal rod 17 extends beyond the nut 27 to receive the usual

6 thumb nut 28 to constitute a familiar type of binding post for the plug. The shoulder piece 29 constitutes a limiting stop between which and the nut 27 the parts are clamped together.

70 The said insulator washer or disc 24 is peripherally beveled oppositely from a median plane towards its upper and lower sides, being of largest diameter at said median plane. Thus the path of current leakage between the upper and lower washers is considerably increased, with the result of ample insulation between the gland neck and the outer end of the terminal rod. This formation of the insulator washer also gives it the 75 additional function of diverting water, which may fall on the washer, outwardly away from the parts of the plug body. The neck 16 can be formed below the insulating washer with fins 38 to constitute the elements 80 of a radiator to maintain suitably cool the exposed portions of the plug. It will be noted also that said fins are of gradually decreasing diameter from the inner end of the neck outwardly and that the peripheries of the fins are beveled so as to avoid lodgement 85 of water on this part of the plug. The fin formation materially lightens the plug.

90 The construction described, wherein the insulator tube or sleeve 23 is enclosed by the metallic neck 16 or analogous part of the metal body of the plug, possesses considerable practical advantage, inasmuch as the plug is free of exposed insulating parts, as 95 the usual porcelain insulator, which are liable to be fractured, and which, upon fracture, short circuits the plug. The plug is, therefore, sturdy and capable of hard usage 100 without injury.

105 Referring now to the construction of the inner end of the shell and to the means for protecting the terminals from contact with oil which may be pumped into the cylinder, the parts are made as follows:

110 The said inner end of the shell is of general part-spherical, or concavo-convex formation. It is formed diametrically across said end with a deep groove 31 having a flat bottom member 32 that constitutes a baffle element, as will hereinafter more fully appear. The plane of said element 32 is considerably above or exterior to the inner concave surface of said end, as best shown in Figures 2 and 5, thereby forming at the sides 115 of the groove 31 segmental chambers 33 bounded by spherically segmental walls 34. 35, 35 designate slits that are cut into the spherically shaped end wall at opposite sides of the shell. The plane of said slits is transverse to the plane of the axis of the shell and preferably below or inside the plane of the baffle element 32, as best shown in Figure 5. The baffle element 32 is wider than the slit 31, so that its side edges extend laterally 120 beyond the inner or proximate edges of the 125

end wall segments 34, and such oil as may find its way to the chamber 30 is by the edges 36 of the baffle member 32 thrown outwardly against the side wall of the shell and away from the terminals or electrodes. When the end wall is so formed, the grounded terminal may be supported on the cross or baffle element 32.

As a result of the end wall formation thus described, it will be noted that there are provided at the inner end of the plug shell numerous indirect passageways for the entrance of the burning mixture to the chamber 30 and the discharge of burning gases therefrom, as indicated by the arrows in Figure 5. While said passages provide for free intake and outlet of the gases to and from the chamber 30, the portions of the shell end which remain, and which bound the indirect passage ways, constitute the baffle elements 32, 34, which prevent discharge of oil directly into said chamber for contact with the terminals. The spherical contour of the baffle elements 34 serves to throw oil, directly striking the same in the direction of the axis of the shell, past or across the slits 35, and the baffle element 32, wider than the slot or groove 31, prevents direct entrance of oil from the cylinder to said chamber 30, such oil falling back into the cylinder, or if driven with sufficient force may be directed laterally outwardly through the side slits. It will be furthermore noted that oil tending to enter the chamber 30 through the side slits 35 when the plug occupies a position at an angle to the vertical, either normally or by reason of tilting or turning movement of the engine, will be deflected by the baffle element 32 and pass through the plug end either directly from one slit to the other, or from one slit 35 through the diametric opening or slot 31. Moreover, any oil which is forced into the chamber 30 is deflected by the edges of the baffle element 32 towards the side wall of the chamber and away from the terminal points, and such oil as may thus find its way to the chamber flows freely from the wall through the openings 31 or 35.

It will thus be observed that, while provision is made for free ingress of gas to and exit of the flaine from the chamber 30, more stable and viscous fluids, such as lubricating oil, which is being pumped by the pistons into the cylinders, is deflected or baffled away from the chamber 30 and from the terminals, and is, therefore, prevented from finding its way to the terminals.

The said indirect passageways and baffle elements at the inner end of the plug shell can be constructed in a variety of ways. A convenient way to manipulate the shell to form these elements, when the shell is formed by automatic screw machine operations, is to produce the inner concave or

spherical face of the inner wall of the shell by the tool that bores out the chamber 30 and to thereafter produce the outer or convex spherical surface of said end wall by the tool which reduces the portion 11 of the shell 70 on which the screw thread is formed, and which tool has an extension cutter for engagement with that portion of the stock which constitutes, in the final product, said end wall. After the shell has thus been 75 produced, it has a solid spherical end. Thereafter the groove or slot 31 can be formed by placing said shell over a suitable die and forming the spherical end thereon by means of a suitably shaped punch. The 80 die and punch will be shaped to permit lateral displacement of the metal which finally forms the baffle element 32. Thereafter the slots 35 can be cut into the sides of the reduced portion of the shell by suitable cutters.

In order to assist in properly spacing the terminals at the air gap, the reduced portion 11 of the plug shell can be provided with oppositely disposed side openings 40 to 90 permit the person adjusting the terminals to observe the adjacent ends of the terminals and the width of the spark gap.

A convenient way of varying the width of the spark gap is to provide between the shoulder 15 of the gland and the opposing shoulder on the shell, in addition to the usual packing washer 41, a second washer 42, which is a laminated or shim washer of such structure that one or more laminae may 100 be removed therefrom to reduce the width of the spark gap.

A further advantage of the chambered construction at the inner of the shell is that said chamber and terminals are soot proof. 105 This is due, in part, to the fact that lubricating oil does not find its way to the terminals, which in the use of the ordinary spark is a large factor in producing carbon or soot deposits. It is also due to the fact that the ignition of the gases in said chamber 30 and the withdrawal of the ignited gases, when the exhaust valve is opened, produces a condition within the chamber and at the terminals which is not favorable for the 110 deposit of carbon. It has been found in practice that a plug having a chamber of substantial size, as shown in the drawings, which communicates with the cylinder through restricted passages, is more actively 115 self-cleaning of carbon and soot deposits than a chambered plug which is freely open at its cylinder or inner open end.

While the structure of the plug has been 120 described in considerable detail, it will be understood that the scope of the invention is not intended to be thereby limited, except as to claims where such details are specifically set forth and as imposed by the prior art. 125 It is the intent, therefore, to claim all of 130

inherent novelty shown in the drawings and described in the specification.

I claim as my invention:

1. A spark plug embracing a body formed at its inner end with a chamber enclosing spaced, central terminals, the inner or end wall of said chamber being provided with a passage which permits free ingress of gas to and egress of burning mixture from said chamber and with a baffle element between the passage and terminals wider than said passage, with its edge so related to the wall of the passage as to deflect oil entering the chamber outwardly away from said terminals, said chamber wall being provided opposite said edges with lateral passages.

2. A spark plug for the ignition system of explosion engines comprising a shell, a live terminal insulated from said shell and extending into a chamber at the inner end of said shell, and a terminal grounded on said shell wholly within said chamber and spaced from the live terminal by a spark gap, the wall of said chamber at the inner end of said shell being formed at its inner end and sides with outwardly and laterally indirect passageways for gases formed by overlapping baffle elements which baffle entrance to said chamber of cylinder oil.

3. A spark plug embracing two terminals between which is formed a spark gap and a supporting body therefor having at its cylinder end a chamber to wholly enclose said terminals, the end wall of said chamber being part spherical and formed with an inwardly opening diametric slot bounded at its outer side by a baffle element, and the sides of said wall being provided with opposed slits which open laterally toward said chamber substantially opposing but lower than the edges of said baffle element.

4. A spark plug embracing two terminals between which is formed a spark gap and a supporting body therefor having at its cylinder end a chamber to wholly enclose said terminals, the wall of said chamber being part spherical and formed with an inwardly opening diametric slot bounded at its outer side by a baffle element, and the sides of said wall being provided with slits which open laterally toward said chamber, said baffle element being wider than said slots.

5. A spark plug embracing two terminals between which is formed a spark gap and a supporting body therefor having at its

cylinder end a chamber to wholly enclose said terminals, the wall of said chamber being part spherical and formed with an inwardly opening diametric slot bounded at its outer side by a baffle element, and the sides of said wall being provided with slits which open laterally toward said chamber, the lateral slits being located in a plane inside the plane of said baffle element.

6. A spark plug embracing two terminals between which is formed a spark gap and a supporting body therefor having at its cylinder end a chamber to wholly enclose said terminals, the wall of said chamber being part spherical and formed with an inwardly opening diametric slot bounded at its outer side by a baffle element, wider than said slot, and the sides of said wall being provided with opposed slits which open laterally toward said chamber, the said grounded terminal being supported on said baffle element.

7. A spark plug comprising a shell open at its outer end, a grounded terminal supported by the inner end of said shell, an elongated tubular gland member closing said shell, a live terminal member cooperating with the grounded terminal and extending outwardly through said tubular gland member, an insulator tube within said tubular gland member and surrounding said live terminal member to a point beyond the gland member, and an insulating disc having means to press it against the outer end of said gland member and formed to receive the outer end of said insulator tube.

8. A spark plug comprising a shell open at its outer end, a grounded terminal supported by the inner end of said shell, an elongated tubular gland member closing said shell, a live terminal member cooperating with the grounded terminal and extending outwardly through said tubular gland member, an insulator tube within said tubular gland member and surrounding said live terminal member to a point beyond the gland member, and an insulating disc having means to press it against the outer end of said gland member and formed to receive the outer end of said insulator tube, said disc overhanging the upper end of said gland and being formed with a tapered or wedge shaped periphery.

In witness whereof I claim the foregoing as my invention, I hereunto append my signature this 12 day of January, 1921.

FRANK S. ROYER.
